UNITED STATES PATENT OFFICE.

JOHN MAGAZZINI, OF NEW YORK, AND FRANCIS J. DOWD, OF SUFFERN, NEW YORK.

FAUCET.

Application filed April 12, 1927. Serial No 183 084.

The present invention relates to faucets and particularly to faucets for separately discharging either of two liquids from the faucet or discharging a desired mixture of the liquids from the faucet, the device being more particularly intended for use with hot and cold water and in association with wash-basins, bath tubs, sinks and the like, and one object of the invention is to provide a faucet of the character mentioned in which the use of spring operated valve members is obviated.

Another object is to provide a device of the character mentioned in which the use of valve handles for operating the valves is obviated.

A further object is to provide a device of the character mentioned which is easily attached to the substantially standard arrangement of sources of supply of liquids, commonly found in buildings, such as the sources of supply of hot and cold water, the device being of uncomplicated parts and cheap to manufacture, simple and easy to use, not liable to get out of order, and easily cleaned.

A feature of the invention is the use of ball valve members which are maintained in closing position by pressure of the liquid on the ball valve members, these members being severally moved to open position for separate discharge from the device of the particular liquid desired, and being jointly moved to open position for discharge of a mixture of the liquids, by operation of a swinging nozzle cooperating with the ball valve members and having a conduit operating at one time for passage therethrough of the liquid desired to be discharged separately and operating at another time for passage therethrough of a mixture of the liquids, this conduit then constituting a mixture chamber for the liquids as well as means for discharging the liquids.

We attain these objects and such other objects as may later appear herein, by the invention one of the possible embodiments of which is described by way of example in the subjoined specification and shown in the accompanying drawing forming part of the specification, it being understood that we may make modifications and variations of the invention without departing from the spirit thereof or exceeding the scope of the appended claims.

In said drawing, Fig. 1 is a plan view of the device.

Fig. 2 is a side elevation of the device.

Fig. 3 is a bottom view of the device, the valve seat disk being removed for showing the outlet ends of the valve chambers.

Fig. 4 is a fragmentary sectional view on the line 4—4 of Fig. 1, the swinging valve-operating nozzle being moved to position whereby the valve members are in position for closing both the valve chambers.

Fig. 5, is a sectional view similar to Fig. 4, except that the swinging valve-operating nozzle is moved to position whereby the valve members are in open position for passage of substantially equal amounts of liquid from the two valve chambers.

Fig. 6, is a detail plan view of the valve seat disk, and

Fig. 7, is a plan view showing the inlet end of the swinging valve-operating nozzle, and showing the undulating or cam faces on the end edge of this member.

Referring to Fig. 1, the device embodies two intake members or heads 10 and 11, spaced apart preferably in alinement and each provided with means such as the threaded nipples 12 and 13 for connection to a source of supply of liquid, in the present instance the nipple 12 being connected to a source of supply of hot water and the nipple 13 to a source of supply of cold water.

The valve casing 14 is arranged intermediately of the intake members 10 and 11, Figs. 4 and 5, and has therein the adjacently disposed chambers 15 and 16, open at their bottoms, the chamber 15 communicating by the conduit 17 with the intake member 10 and the chamber 15 communicating by the conduit 18 with the intake member 11. The valve casing 14 has on its under or bottom side the annular flange 19, interiorly threaded near its free end and providing the interior space or chamber 20 communicating with both the chambers 15 and 16.

The valve operating nozzle 21 has at one end thereof the curved end portion 22 and has at its other end the oppositely curved end portion 23; the end portion 22 has at its end the outwardly and upwardly extending annular flange 24. The nozzle 21 has adjacent the flange 24 at the open end of the bore of this member the undulating end face edge 25, the raised or higher portions of the undulations constituting cam surfaces for the purpose later stated, an annular groove or channel 26 being formed between the flange 24 and the end face 25.

The valve seat disk 27 is in diameter adapted to engage closely in the space or chamber 20, and is provided with the circular valve seats 28 and 29 arranged to register with the 5 circular bottom openings of the chambers 15 and 16, and is provided with the alined screw holes 30.

The valve members 31 and 32 are balls of any suitable metal or material and are adapted 10 to seat in water tight position in the valve seats of the disk 27.

In assembling the device the gasket 33, conforming in shape, valve seats and screw holes to the valve seat disk 27, is disposed 15 in the space or chamber 20 flat against the end faces of the chambers 15 and 16. The valve seat disk 27 is disposed flat against the gasket 33, the valve seats of the gasket and disk and screw holes of the gasket and disk 20 registering; the ball valve members 31 and 32 being disposed in the chambers 15 and 16 so as to seat in the valve seats formed by the 25 gasket and disk, and the disk is secured in place in water tight manner by screws, not shown, passing through the screw holes of the disk and gasket into the partition wall between the chambers 15 and 16. The annular washer 34 is disposed flat against the under side of the disk 27 and the curved end 22 30 of the operating nozzle 21 is inserted in the space or chamber 20 so that the end face of the upstanding portion of the flange 24 lies flat against the washer 34; the annular washer 35 is disposed flat against the under side 35 or shoulder of the flange 24 and the bushing 36 is threadedly secured in the space 20 whereby the end 22 is held in place in the space or chamber 20 in a water tight manner but is rotatably or swingingly movable therein.

In Figs. 2 and 4 the operating nozzle 21 lies in a plane substantially parallel to and below the plane of the alined conduits 17 and 18 and both the ball valves are received 45 in depressions or low portions of the undulating or cam surface of the nozzle 21 and thereby close both chambers 14 and 15; by moving or swinging the nozzle 21 at an angle to the line of the conduits 17 and 18, as to the position A, Fig. 1, one of the ball valves rides up on a high portion of the cam surface to full open position and permits full flow from 50 one of the chambers while the other ball valve is in a depression of said surface and closes the other chamber; by further movement of the nozzle 21 toward the position M the second ball valve is gradually raised and the second chamber is opened for mixing to a degree the water from the chambers, when 55 the nozzle 21 is moved to the position M both valves ride up on high portions of the cam surface as shown in Fig. 5, and the mixture from the chambers is of equal parts, it being borne in mind that the operating of the 60 nozzle 21 is the same on both sides of M; on 65

the side A, the cold water is tempered by hot water and on the side B the hot water is tempered by cold; it is also seen that the faucet is completely closed by moving the nozzle 21 either to left or right to lie substantially parallel to the conduits 17 or 18.

The operating nozzle 21 may be provided with the insulated knob or handle 37 to prevent burning when the nozzle is manipulated during discharge of hot water, and protective bumpers 38 may be provided between the nozzle 21 and the intake members 10 and 11.

What we claim and desire to protect by Letters Patents is:

1. The combination with means for supplying liquid, of intake members, a valve casing having chambers severally communicating with different ones of said intake members, outlet valves in said chambers, and a combined discharge nozzle and valve actuating means cooperating with said valves.

2. The combination with means for supplying liquid under pressure, of intake members, a valve casing having chambers severally communicating with different ones of said intake members, outlet valves in said chambers normally retained in closing position by pressure of the liquid received from said means for supplying the same, and a combined discharge nozzle and valve actuating means cooperating with said valves.

3. The combination with means for supplying liquid, of intake members, a valve casing having chambers severally communicating with different ones of said intake members, said chambers having valve seats providing outlets from said chambers, valve members in the chambers engageable with said valve seats, and a nozzle having a discharge bore communicating with said valve seats for receiving liquid from said chambers and an end face engageable with said valve members for actuating the valve members.

4. The combination with means for supplying liquid, of intake members, a valve casing disposed between said intake members and having adjoining chambers therein, a conduit connected to one of said intake members and to one of said chambers, a second conduit connected to the other of said intake members and to the other of said chambers, an outlet valve in each of said chambers, and a combined discharge nozzle and valve actuating means cooperating with the outlet valves of both said chambers.

5. The combination with means for supplying liquid, of intake members arranged in spaced alinement, a valve casing disposed intermediately of said intake members and in alinement therewith and having adjoining chambers therein, a conduit connected to one of said intake members and to one of said chambers, a second conduit connected to the other of said intake members and to the other of said chambers, an outlet valve in each of

said chambers, and a combined discharge nozzle and valve actuating means cooperating with the outlet valves of both said chambers.

5 6. The combination with means for supplying liquid, of intake members arranged in spaced alinement, a valve casing disposed intermediately of said intake members and in alinement therewith and having adjoining 10 chambers and a flange extending below the bottom of said chambers and forming a chambered space adjoining the bottoms of said chambers, a conduit connecting one of said intake members and one of said chambers, a second conduit connecting the other 15 of said intake members and the other of said chambers, a disk disposed in said chambered space and closing both said chambers at their bottoms and having a valve seat 20 opening for such chamber, a ball valve in each chamber engaging the valve seat opening appurtenant to the chamber, and a nozzle having an inlet end portion rotatably disposed in said chambered space and having 25 a bore communicating with said chambered space and an end face engageable with both of said ball valves for actuating the valves.

7. In a device of the character described, a discharge nozzle having at the intake end

of its bore an undulating valve actuating 30 end face.

8. In a device of the character described, in combination, ball valve members, and a swingingly movable discharge nozzle having at the intake end of its bore an end face 35 comprising alternate high portions and low portions for actuating the ball valve members when the nozzle is swingingly moved.

9. In a device of the kind described, a valve casing having chambers provided with outlet 40 valves including ball valve members, and a combined discharge nozzle and valve actuating means cooperating with said ball valve members.

10. In a device of the kind described, a valve casing having chambers provided with outlet valves including ball valve members, and a movable nozzle having a bore cooperating 45 with the outlet of said valves and an undulating end face engageable with said ball valve members for actuating said members when said nozzle is moved.

Signed at New York, in the county of New York and State of New York, this 11th day of April, A. D. 1927.

JOHN MAGAZZINI.
FRANCIS J. DOWD.
